UNITED STATES PATENT OFFICE.

JOHN FRANCIS POPE, OF CHICAGO, ILLINOIS.

SPRING-SEAT.

SPECIFICATION forming part of Letters Patent No. 670,483, dated March 26, 1901.

Application filed July 15, 1899. Serial No. 723,991. (No model.)

To all whom it may concern:

Be it known that I, JOHN FRANCIS POPE, a citizen of the United States, residing at Chicago, in the county of Cook and State of Illinois, have invented a new and useful Spring-Seat, of which the following is a specification.

My invention relates to improvements in vehicle spring-seats, more especially for bicycles, by the use of vertical voluted springs placed under and supporting the seat-covering, thereby giving the seat that resilience so necessary to the comfort of the rider.

My invention consists of an upper frame, to the perimeter of which the leather or other seat-covering is attached, provided with inverted case-like pockets, which pockets fit onto vertical voluted springs mounted on the ends of projecting arms or shafts diverging from a point supported on the vehicle. The action of these vertical springs under pressure gives the seat a comfortable resilience. I attain this object by the mechanism illustrated in the accompanying drawings, in which—

Figure 1 represents a plan or top view of the entire seat with the surface-covering removed. Fig. 2 is a vertical section along the broken line W V, Fig. 1; and Fig. 3 is a vertical section along the broken line X Y of Fig. 1.

Similar letters refer to similar parts throughout the several views.

A represents the more or less central point of the lower framing of the seat where it rests on the vehicle, whence the arms or shafts b, c, and d project to bear the vertical voluted springs S, which are mounted at the terminal points b', c', and d', respectively, of these arms.

e and e' represent, respectively, the sides and top of the framing of the inverted pocket-like cases which fit on top of the vertical springs S. In Fig. 1, e' is removed to better show the plan of the pocket-framing.

f represents the framing of the perimeter of the seat-surface, to which the leather or other covering is attached.

g represents the continuation of the framing e to connect with the framing f for additional strength.

h represents the leather or other surface-

covering of the seat attached to the perimeter of the frame f.

k represents a means of attaching the whole seat-framing to a projecting bar or rod of the vehicle.

The projecting arms or shafts b, c, and d are preferably curved upward for greater strength, and the springs S are preferably secured on their arms or shafts by a shoulder on the inner side and a nut on the outer end, screw-threaded to receive the nut. An additional lock-nut may be provided for greater security. The bearings b' c' d' immediately supporting the vertical voluted springs S should preferably be of a square or rectangular section. The springs S should preferably have their volutes turned on a square axis, with the volutes close together at bottom, thus giving greater resilience to their upper portion for the same diameter of spring. The pockets e and springs S may be fastened together by a wire or chain through the upper volute.

If necessary, the seat-cover may be directly supported on top of the vertical voluted springs S and secured to the upper volute of the spring. In such case the pocket e would be dispensed with. The perimeter of this frame f may be of any convenient shape suitable for a seat.

I am aware that prior to my invention vehicle-seats have been supported on springs, and I do not, therefore, broadly claim all springs; but

What I do claim as my invention, and desire to secure by Letters Patent, is—

A vehicle-seat comprising a cover-frame having open-bottom pockets in its under side, a plurality of arms radiating from a common center, and a corresponding series of voluted springs mounted each on one of said arms, each spring being vertically disposed and secured at its center to one of the arms, the outer volute of the springs fitting within the several pockets of the cover-frame, substantially as set forth.

JOHN FRANCIS POPE.
